UNITED STATES PATENT OFFICE.

JAMES H. DEAN, OF LUDINGTON, MICHIGAN, ASSIGNOR TO NORTHWESTERN EXPANDED METAL COMPANY, OF CHICAGO, ILLINOIS, A CORPORATION OF ILLINOIS.

SHEET-METAL LATH.

Application filed September 18, 1925. Serial No. 57,130.

This invention relates to improvements in ribbed lath made from expanded sheet metal. The invention consists in a ribbed lath having longitudinally extending ribs formed in 5 unslotted sections of the lath with diamond-shaped meshes arranged between the ribs and with the meshes of the central row of greater area than the other meshes, whereby in applying plaster to the laths the portion of the 10 plaster that is forced through the central row of large meshes will form a key or lock to hold the plaster in place while only small portions of the plaster will be forced through the smaller meshes.

15 This construction thus secures quite a saving in plaster over what is required when the meshes are all of the size of the large mesh. In other words, by making all of the meshes narrow except those of the central row I lock 20 the plaster securely to the lath and use a minimum amount of plaster.

The invention consists generally in the construction and combination hereinafter described and particularly pointed out in the 25 claims.

In the accompanying drawings forming part of this specification.

Figure 1 is a plan view of a section of sheet metal with the ribs formed therein and 30 with the sheet slotted to produce my newly invented lath;

Figure 2 is an elevation showing a section of the lath in position on an upright building stud;

35 Figure 3 is a section of line 3—3 of Figure 2;

Figure 4 is a similar section showing the plaster applied thereto.

In the drawings 2 represents a sheet of 40 metal such as is generally used in the making of expanded metal lath. This sheet is provided with unslotted longitudinally extending portions 3, 3, 3 in which are formed the parallel longitudinally extending ribs 4, 4, 4.

45 I form in each longitudinal space between the ribs a series of diagonally extending parallel slits 5, 6, the slits between any two of the ribs diverging from the slits between the next adjacent ribs as clearly seen in Figures 50 1 and 2.

After the longitudinal ribs 4 are formed and the slits 5 as shown in Figure 1 are produced by any suitable means, the sheet is expanded into the form shown in the other 55 figures of the drawing. As one strand of

each of the outer diamond meshes is formed by the margin of the unslotted portion of the sheet the two outer rows of meshes will not be opened to as great an extent as the center row of meshes. The center meshes will therefore be of greater area than the marginal meshes and when the lath is in position, as shown in Figures 2, 3 and 4 of the drawings, and plaster is applied thereto, a considerably larger amount of plaster will pass 60 through the center meshes forming a key or lock for the plaster at the back of the lath, as shown in Figure 4 of the drawing. These locks will be formed with every central row 65 of meshes and thereby the sheet of plaster will be firmly and securely locked to the lath. Only a small amount of plaster will pass through the marginal meshes as indicated in Figure 4.

I have indicated the strands of the outer 70 meshes that are formed by the edges of the unslotted portions of the sheet by the reference numerals 7, 7; the strands of the outer meshes that are connected to said unslotted 75 portions by the reference numerals 8, 8, and 80 the strands enclosing the central meshes by the reference numerals 9 and 10, the strands 9 being common to both the central and the outer meshes.

As will be seen by the sectional drawings 85 (Figures 3 and 4) the strands 7 and 8 are practically parallel with the outer or finished surface of the applied plaster and in substantially the same plane as the unslotted portions of the sheet, while the strands 9 and 90 10 stand nearly on edge or at a substantial angle to the plane of the unslotted portion of the sheet, thus making it easier for the plaster, when applied, to pass between the edgewise strands and through the central 95 meshes.

By providing the central rows of large 100 meshes a secure bonding of the plaster to the lath is obtained and there is a material saving in the amount of plaster used over what would be required if the meshes were all of the large size here indicated for the central rows. By this construction I also secure lath of proper width with a minimum amount of steel to which the plaster can be securely 105 bonded. Heretofore, so far as I am aware, all of the meshes in any sheet of expanded metal lath have been of uniform size or area.

I claim as my invention:

1. A lath comprising a metal sheet hav- 110

- ing a series of parallel unslotted sections extending longitudinally of the sheet with longitudinally extending ribs formed centrally in said unslotted sections, diamond shaped meshes arranged along the margins of said unslotted sections, one wall of each mesh being formed by an edge of an unslotted section, the other walls of each said mesh being formed by strands each having one end integral with the edge of the unslotted section and extending diagonally therefrom, and strands formed integrally with and connecting the ends of said diagonal strands and extending substantially parallel with the edges of the unslotted sections, strands extending diagonally between said last named strands and forming therewith a row of diamond shaped meshes of larger area intermediate the marginal meshes.
- 20 2. A lath comprising a metal sheet having a series of parallel unslotted sections extending longitudinally of the sheet with

three rows of diamond shaped meshes arranged between each pair of unslotted sections, the meshes of the central row being of greater area than the meshes of the other rows.

3. A lath comprising a metal sheet having a series of unslotted sections extending longitudinally of the sheet with a plurality of 30 rows of meshes arranged between each pair of unslotted sections, the meshes of the central row being of greater area than the meshes of the other rows.

4. A lath comprising a metal sheet having 35 a series of unslotted sections extending longitudinally of the sheet with a plurality of rows of expanded meshes between each pair of unslotted sections and said meshes varying in area. 40

In witness whereof, I have hereunto set my hand this 14th day of September, 1925.

JAMES H. DEAN.
